DESIGN FOR A LAUNDRY UNIT

William J. Russell, Mansfield, Ohio, assignor to Westinghouse Electric & Manufacturing Company, a corporation of Pennsylvania

Application October 29, 1942, Serial No. 108,632

Term of patent 14 years

To all whom it may concern:

Be it known that I, William J. Russell, a citizen of the United States, residing at Mansfield, in the county of Richland and State of Ohio, have invented a new, original and ornamental Design for a Laundry Unit, of which the following is a specification, reference being had to the accompanying, drawing, forming a part thereof.

Fig. 1 is a perspective view of a laundry unit
embodying my new design.

Fig. 2 is a view similar to Fig. 1 with the access openings in their open position.

The end of the unit not shown is substantially similar in appearance to the end in view.

I claim:

The ornamental design for a laundry unit, substantially as shown and described.

WILLIAM J. RUSSELL.
